PACKAGE-BINDING TOOL SUPPORT

George A. Crosby, Park Ridge, and Arvid I. Ericsson, Chicago, Ill., assignors to Signode Steel Strapping Company, Chicago, Ill., a corporation of Delaware

Application August 11, 1944, Serial No. 549,002

8 Claims. (Cl. 248—280)

1

Our invention relates to package-binding tool supports. That is to a support for carrying a tool used in the application of tensioned reinforcing or binding strap or wire about packages. Its purpose is normally to hold the package-binding tool in proximity to—preferably above—the space on a shelf or bench where package-binding is to be done, but to permit the operator transiently to shift the tool to the surface of the package for binding. By the use of such supports, tools are less apt to be dropped and damaged and operators are able to bind packages in quantity faster and with less fatigue.

The principal object of the invention is to provide a tool support that is simple, light, inexpensive, effective for the intended purpose, readily adjustable for varying conditions, and easy to manipulate.

Other objects and advantages will hereinafter appear.

The preferred embodiment of our invention is shown in the accompanying drawings, wherein

Fig. 1 is a side elevation of a tool support showing how its base or foot may be adjusted for attachment to the floor or to the side of a work bench or other vertical wall; the full lines show the support in normal or inactive position with the tool away from the package, and the dot-dash lines indicate it in a condition assumed with the tool in binding position resting on a package;

Fig. 2 is an enlarged side elevation of the tool support, showing in full lines an intermediate position and in dot-dash lines the active position. In both positions a binding tool is indicated by dotted lines;

Fig. 3 is an enlarged top plan partly in section;

Fig. 4 is an enlarged section on the line 4—4 of Fig. 2;

Fig. 5 is a section on the line 5—5 of Fig. 2;

Fig. 6 is a section similar to Fig. 5 with the supporting arm swung ninety degrees;

Fig. 7 is a partial top plan showing the supporting arm swung ninety degrees from the position of Fig. 3;

Fig. 8 is a section on the line 8—8 of Fig. 3;

Fig. 9 is an enlarged section on the line 9—9 of Fig. 3;

Fig. 10 is a section on the line 10—10 of Fig. 9;

Fig. 11 is a section on the line 11—11 of Fig. 9;

Fig. 12 is an enlarged elevation of the arm camming member and adjacent portions of the support pedestal;

Fig. 13 is an enlarged elevation and partial section of the attaching foot or bracket of the support secured to the floor;

2

Fig. 14 is a section on the line 14—14 of Fig. 13; and

Fig. 15 is a view similar to Fig. 14 but with the foot or bracket secured to a side wall or bench.

In general, the tool support includes a tubular telescopic pedestal A, which for convenience may be attached by a foot or bracket B either to the floor adjacent a work bench or shelf C or to the wall or side of the work bench, a laterally projecting arm D, which is pivotally carried by the upper end of the pedestal and extends laterally therefrom so that its free end may be brought over the space on the bench or shelf where a package rests in binding position, and a tool carrier E, which is pivoted to the outer or free end of the arm D and adapted to be attached in some appropriate manner to the binding tool to be supported. The arm and tool carrier are spring biased so as normally to hold the tool far enough from the package space to enable a package to be placed in binding position without interference. By slight effort, however, the operator may bring the tool to binding position flat against a surface of the package and, after completion of the binding operation, easily return the tool to its normal or out of the way position.

Merely by way of example and to afford a better understanding of the purpose of the support, it is indicated as carrying a package binding tool of the type set forth in John H. Leslie, II, application Serial No. 514,343, filed December 15, 1943.

The pedestal A is composed of two telescopic tubular sections 5 and 6. Preferably the sections are formed from lengths of steel pipe of slightly different diameters. Outer section 5 is pivotally attached near its lower end to the foot or base bracket B. This foot B is formed with two upstanding spaced flanges 9 and 10 between which the lower end of outer pedestal section 5 lies. The pivotal connection between the foot and the outer tubular section is effected by means of a pivot bolt 11 and preferably, in order to provide a longer operating surface and thereby insure greater lateral rigidity, a section of tubing 12 passing through aligned holes in and welded to outer section 5, forms an elongated bearing for the bolt 11. Pivot bolt 11 passes through aligned holes in the two foot flanges 9 and 10 and axially through the bearing provided by the sleeve 12. This construction is shown most clearly in Fig. 13.

Foot B is formed with a pair of parallel webs 15 and 16 which lie between flanges 9 and 10 and are separated far enough apart for the lower end

of outer pedestal section 5 to lie loosely therebetween, as shown most clearly in Fig. 14. Webs 15 and 16 have threaded holes therethrough for abutment screws 17 and 18, respectively. These two abutment screws 17 and 18 serve as adjustable stops for engaging either the lower end of section 5 or a stop lug 25 rigidly projecting from the lower section 5 to limit the forward and backward swing of the support pedestal about pivot bolt 11, depending upon whether foot B is attached to the floor or a vertical wall. Adjustment may be retained by lock nuts 27 and 28. Foot flanges 9 and 10 have laterally directed attaching flanges 29 and 30, respectively, which are provided with holes for screws 31 and 32, respectively, for anchoring the foot to the floor or to a vertical wall as desired. When, as shown in the full lines of Fig. 1 and in Figs. 2, 3, 4, 7, 13 and 14 the pedestal foot is anchored to the floor, the cap abutment screws 17 and 18 are located on opposite sides and in the path of movement of lower pedestal section 5, and thereby the forward and backward swing of pedestal A about pivot bolt 11 is limited by the adjustment of screws 17 and 18. When the base is anchored to a vertical surface, the adjustment cap screws are located on opposite sides of stop lug 25 as shown in Fig. 15 and the engagement of that stop lug against screws 17 and 18 limits the forward and rearward swing of the pedestal.

The upper end of outer pedestal section 5 has a rectangular collar 35 welded or otherwise rigidly fastened thereto. The forward half of the top surface of collar 35 lies horizontally, whereas the rear half thereof is inclined to provide the beveled surface 36 for a purpose to be presently explained. Collar 35 has an upstanding flange 37 along its rear edge which serves to limit the permissible relative rotation between the telescopic pedestal sections 5 and 6 to the desired amount; as shown, to one hundred eighty degrees, or ninety degrees each side of the central operative position.

The internal upper telescopic section 6 of the pedestal is provided with an adjustable collar 38 which has a hole therethrough only slightly larger than the external diameter of section 6 so that the section may be slid axially therethrough. However, the collar is provided with a radial slot 39 and aligned holes 40 and 41—the former being threaded and the latter unthreaded—at right angles thereto for the reception of a clamp screw 42. By means of this clamp screw 42 the sections of collar 38 on opposite sides of slot 39 may be drawn together so as to cause the collar tightly to grip pedestal section 6 and thereby become immovable with respect thereto; or the collar may be forced or permitted to expand to enable the pedestal section 6 to be moved axially therethrough in either direction. Normally collar 38 of section 6 rests upon collar 35 at the top of section 5 so that by adjusting the position of collar 38 upon section 6, it is possible to vary the extent to which the pedestal is extended or shortened so as to adapt the vertical height of the arm of the tool holder for different conditions—such as different heights of the binding bench or of the packages being bound.

Clamp screw 42 carries a ring or washer 43 which lies in the slot 39 of collar 38 and projects into a longitudinal slot 44 in the upper smaller tubular section 6, thereby preventing relative rotation between the upper tubular section and the height adjusting collar 38 so that the two always rotate together whether or not the adjustable

collar is clamped to the upper tubular section. In general the adjustable collar 38 is semi-circular so that it may be rotated relative to fixed collar 35 until one or the other of its flat sides strikes flange 37 whereupon further relative rotation is prevented. Thus as most clearly indicated in Figs. 5 and 6, the upper tubular pedestal section 6 and the height adjusting collar 38 can be rotated relative to the lower larger pedestal section 5 for 180°. The lower surface of the rear half of collar 38 is beveled, as at 45, corresponding to the beveled surface 36 of collar 35. These confronting beveled surfaces cause the telescopic section 6 and the tool supporting arm carried thereby normally to tend to lie with the arm over a package in binding position.

The lateral tool supporting arm D at the top end of the telescopic pedestal includes an angular bracket consisting of a pair of parallel side plates 55 and 56, which are rigidly attached in spaced relation to the top end of the smaller upper pedestal section 6. The preferred attachment is shown most clearly in Figs. 2 and 9. It is formed by providing the top open end of section 6 with four longitudinally extending slots cut or milled therein in aligned pairs; and into each pair one of the side plates 55 or 56 is rather snugly fitted and then welded into position.

Between the side plates 55 and 56 lie parallel levers 57 and 58 which are pivoted thereto by a common pivot pin 59. This pin is retained in place by suitable means, such as cotter pins 60.

The outer ends of levers 57 and 58 carry the tool carrier E. This carrier includes a flat stem 65 lying between and pivotally attached to the outer ends of the levers 57 and 58 by a bolt 66 which is retained in place by a suitable nut 67. The form and character of this tool carrier will depend upon the construction of the tool to be supported. In the construction shown the stem 65 of the carrier is bent to form a laterally extending flange 69 which is bifurcated to receive a tool attachment plate 70. Plate 70 is pivotally secured to flange 69 by means of a knurled headed pivot stud 71 which is biased into forward or anchoring position by a spring 72. Any appropriate means may be employed for securing the package binding tool to the attachment plate 70. When stud 71 is raised against the force of spring 72, the plate 70 may be withdrawn from flange 69 for the quick removal of the tool attached to plate 70 and, if desired, the insertion of a different plate for a tool of some other type. When stud 71 is released, its spring 72 urges it downward to retaining position.

A bar or link 75 lies between the levers 57 and 58 and is pivotally attached at its rear end to and between the fixed bracket plates 55 and 56 by a pivot pin 76. The levers 57 and 58 have notches 78 and 79, respectively, for accommodating the protruding ends of pin 76. The forward end of bar or link 75 is extended by a pair of link plates 85 and 86, rigidly attached to opposite sides of the outer end thereof by rivets 87. Thus the link extension plates 85 and 86 lie in the planes of the arm levers 57 and 58, respectively, being accommodated by notches 88 and 89, respectively, in the upper edges of those levers. And link extension plates 85 and 86 are spaced apart so that the stem 65 of the tool carrier may lie between the outer ends thereof.

The tool carrier stem 65 is provided with an elongated slot 95 through which extends a link pin 96 carried by the outer ends of link extension plates 85 and 86. A compression spring 97

lies in this slot, one end against an end of the slot and the other end against pin 96. It is retained against lateral displacement by the two link plates 85 and 86. This spring normally biases the stem of the tool carrier so that link pin 96 lies against the forward end of the slot 95 in the tool carrier stem 65. In operation, however, the tool carrier may be tilted or rocked against the force of this spring. Thus the arm D provides a parallel motion support for the tool carrier stem whereby the tool carrier may be swung vertically about pivots 59 and 76 and yet the stem and the tool are not tilted. However, if, as is the case with some types of binding tools, the tool tends to slide slightly along the package during the binder tensioning operation, the pin and slot connection between the tool carrier stem and the link extensions 85 and 86 enables the tool so to move without causing it to tilt relative to the surface of the package—the biasing spring 97 returning the parts to normal as soon as the tool is released.

In order to facilitate the raising and lowering of the tool carried by the outer end of arm D, the latter is biased or, in effect, counterweighted, by a spring 105 which is housed within pedestal A. The lower end of spring 105 is hooked through the eye 106 of a tension adjusting rod 107. This rod passes through a hole in a guide and abutment cap 108 which fits over the lower end of inner tubular section 6 of the pedestal, as shown most clearly in Figs. 2 and 4. The lower end of the rod 107 is threaded for an adjusting nut 109, which abuts against cap 108 and by its position along rod 107 may vary the effective tension of spring 105. The upper end of spring 105 is hooked into the lower end of a link rod 110 and the upper end of link rod 110 is hooked about a grooved barrel 111 of a pin 112. The opposite ends of pin 112 rest in notches 113 and 114 in arm levers 57 and 58, respectively. Preferably the relation between the arm pivot 59 and the spring pin 112 is such that in the movements of the carrier arm from normal to tool operative position, and vice versa, the effective moment arm of pin 112 varies from a maximum when the spring force is at a minimum to a minimum when the spring force is at a maximum. Thus the force of spring 105 is applied to the tool carrier arm on the side of its pivots 59 and 76 opposite to that of the tool carrier so that, depending upon the adjusted tension of that spring, the tool carrier and the tool carried thereby are urged or biased upwardly away from the space occupied by a package being bound. As desired, this tension may be such as actually to lift the tool from the package unless forcefully held down by the operator or, as may be the better practice to avoid fatiguing the operator, the tension may be only such as substantially to counterbalance the tool so that by very slight effort the operator may lower the tool down into binding position on top of the package and raise the tool after the binding operation to clear the space on the bench for the removal of the bound package and the positioning of the next package to be bound.

Briefly to summarize, the operation and advantages of our tool support are as follows: The foot of the support may be attached either to the floor at the rear of the binding bench or to a vertical wall, such as the back of the bench, as indicated in Figs. 1, 13 and 14 and 15. In the specific embodiment shown in the drawings, the normal or package receiving position of the

tool support is with the upper end of the tubular telescopic pedestal pushed back and the carrier arm in mid position, as indicated by the full lines of Figs. 1 and 3. Also the outer end of the tool carrier arm is elevated, either by the force of spring 105 or by the effort of the operator, depending upon the tension adjustment of spring 105. The work space or position occupied by a package during a binding operation is now cleared so that the operator can locate a package to be bound without interference from the tool or the support.

After the package has been placed in binding position on the surface of the bench, the operator by one composite movement—or by separate movements if desired—can pull the tool forward—the tubular pedestal hinging about its anchorage foot to the position indicated by the dot-dash lines of Fig. 1—swing it horizontally from a location at one side of binding position to directly over binding position—the turning of the inner telescopic pedestal section within the outer telescopic section permitting this movement—lower the tool upon the package to be bound—because of the parallel motion hinging of the carrier arm about pivots 59 and 76—and accommodate the tool to any slight unevenness or inclination of the top surface of the package—permitted by the pin and slot connection between the carrier stem and the link extensions 85 and 86 of the carrier arm.

Upon completion of the binding operation, the operator, by mere reversal of the movements preceding the binding operation, can move the binding tool out of the way for the removal of the bound package and the placement of the next package to be bound.

Having thus illustrated and explained the nature and one embodiment of our invention, what we claim and desire to secure by United States Letters Patent is as follows:

1. A package-binding tool support comprising a pedestal, a bracket secured to the pedestal, an arm pivoted to the bracket and projecting laterally from the pedestal, said arm having an outer end for extending over the package and an inner end extending from the pivot in a direction opposite the outer end, a spring anchored at one end to the pedestal and having the other end anchored at the inner end of the arm to bias the outer end of the arm upwardly away from the package, a tool carrier pivotally connected to the outer end of the arm, a link pivotally connected to the tool carrier and to the rear portion of the arm, the connection with the tool carrier being of the pin and slot variety, and a spring biasing the pin toward one end of the slot.

2. A package-binding tool support comprising a tubular pedestal, a bracket secured to the upper end of the pedestal, an arm pivoted to the bracket and projecting laterally from the pedestal, said arm having an outer end for extending over the package and an inner end extending over the bore of the tubular pedestal, a spring within the bore of the pedestal having one end anchored to the pedestal and the other end anchored at the inner end of the arm to bias the outer end of the arm upwardly away from the package, a tool carrier pivotally connected to the outer end of the arm, a link pivotally connected to the tool carrier and to the rear portion of the arm, the connection with the tool carrier being of the pin and slot variety, and a spring biasing the pin toward one end of the slot.

3. A package-binding tool support comprising

a pedestal, means for anchoring the pedestal either to the floor or a vertical wall, an angular bracket at the top of the pedestal, a tool-supporting arm pivotally connected to and projecting laterally from the pedestal, said arm including a lever pivoted to the bracket and a link also pivotally connected to and projecting laterally from the pedestal in parallelism with the lever, a tool carrier pivotally connected both to the lever and the link of the tool-carrying arm, and a spring anchored at one end to the pedestal and at the other end to the lever for biasing the outer ends of the lever and link upwardly.

4. A package-binding tool support comprising a telescopic pedestal having lower and upper sections, means for adjusting the telescopic relation of the two pedestal-sections, means for anchoring the bottom end of the lower section relative to the package-binding location, a bracket secured to the top end of the upper section, a tool-supporting arm pivotally connected to the bracket and projecting laterally from the pedestal, said arm including a lever pivotally connected to and projecting laterally from the bracket and a link also pivotally connected to and projecting laterally from the bracket in parallelism with the lever, a tool carrier pivotally connected to the lever of the tool-carrying arm and a pin and slot connection between the tool carrier and the link of the tool-carrying arm.

5. A package-binding tool support comprising a pedestal, means for anchoring the pedestal upright adjacent a package-binding bench, a bracket at the upper end of the pedestal, a tool-supporting arm pivotally connected to and extending laterally from the bracket, said arm including a lever pivotally connected to the bracket and a link also pivoted to the bracket and lying in parallelism with the lever, a tool-carrier pivotally connected to the lever of the tool carrying arm, a pin and slot connection between the tool-carrier and the link of the tool carrying arm, and a spring for biasing the tool-carrier pin toward one end of the slot.

6. A package-binding tool support comprising a pedestal formed of two telescopic and rotat-

5 ably related sections, an anchoring foot pivotally attached to one section, a bracket attached to the other section, a tool-supporting arm pivotally carried by the bracket and extending laterally therefrom, said arm including a lever pivotally attached to the bracket and a link also pivotally attached to the bracket and lying parallel to the lever, a tool-carrier pivotally attached to the free ends of the lever and link, and a spring for biasing the free ends of the lever and link upwardly.

10 7. A package-binding tool support comprising a foot for attachment to a floor or side wall; a telescopic pedestal pivotally carried by the foot; said pedestal including a lower tubular section and an upper tubular section longitudinally and axially movable with respect to each other; adjusting means for varying the longitudinal relation between the pedestal sections; and a tool-supporting arm pivotally carried by the upper pedestal section, said arm including a lever, a link and a tool-carrier related to give parallel motion to the tool-carrier.

15 8. A package-binding tool support comprising a foot for attachment to a floor or side wall; a telescopic pedestal pivotally carried by the foot; said pedestal including a lower tubular section and an upper tubular section longitudinally and axially movable with respect to each other; adjusting means for varying the longitudinal relation between the pedestal sections; a tool-supporting arm pivotally carried by the upper pedestal section, said arm including a lever, a link and a tool-carrier related to give parallel motion to the tool-carrier; and a spring for biasing the outer ends of the lever and link upwardly.
